UNITED STATES PATENT OFFICE

130,548

DESIGN FOR A FENDER SHIELD OR SIMILAR ARTICLE

George Albert Lyon, Allenhurst, N. J., assignor to Lyon Incorporated, Detroit, Mich., a corporation of Delaware

Application August 28, 1941, Serial No. 163,060

Term of patent 14 years

To all whom it may concern:

Be it known that I, George Albert Lyon, a citizen of the United States and a resident of the village of Allenhurst, in the county of Monmouth and State of New Jersey, have invented a new, original, and ornamental Design for a Fender Shield or Similar Article, of which the following is a specification, reference being had to the accompanying drawing, forming a part thereof.

On the drawing:

Figure 1 is a side elevational view of a fender shield showing my new design, the dotted outline of a fender being shown for illustrative purposes only; and

I claim:

The ornamental design for a fender shield or similar article, as shown and described.

GEORGE ALBERT LYON.
